UNITED STATES PATENT OFFICE

154,377

DESIGN FOR A MULTIPLE COMPARTMENT
RECEPTACLEBluma Freedman and Morris Farber,
Los Angeles, Calif.

Application June 30, 1947, Serial No. 140,008

Term of patent 3½ years

(Cl. D58—17)

To all whom it may concern:

Be it known that we, Bluma Freedman and Morris Farber, citizens of the United States, residing in the city and county of Los Angeles and State of California, have invented a new, original, and ornamental Design for a Multiple Compartment Receptacle, of which the following is a specification, reference being had to the accompanying drawing, forming part thereof.

Fig. 1 is a perspective view of a multiple compartment receptacle, showing our new design. In this view the cover is in the open position and one of the receptacles has been removed.

Fig. 2 is a perspective view of the receptacle removed from Fig. 1.

Fig. 3 is a bottom plan view of the complete article, the cover being in the open position.

Fig. 4 is a section taken on line 4—4 of Fig. 3.

We claim:

The ornamental design for a multiple compartment receptacle, substantially as shown and described.

BLUMA FREEDMAN.
MORRIS FARBER.
